UNITED STATES PATENT OFFICE.

GEORGE H. ISLEY, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

CONTROL OF REVERSING APPARATUS FOR HEATING FURNACES.

Application filed June 25, 1921. Serial No. 430,431.

To all whom it may concern:

Be it known that I, GEORGE H. ISLEY, a citizen of the United States, residing at Worcester, in the county of Worcester and 5 Commonwealth of Massachusetts, have invented a new and useful Improvement in the Control of Reversing Apparatus for Heating Furnaces, of which the following, together with the accompanying drawings, is 10 a specification.

The present invention relates to improvements in the control of apparatus which is used with the regenerative type of furnace for reversing the course of the burning 15 gaseous fuel through such a furnace.

The present invention relates particularly to the control of the reversing apparatus forming the subject matter of my copending application Serial No. 268,391, filed December 26, 1918. The present invention contemplates various novel and improved features whereby the control of the operation of a reversing apparatus of the above described type is rendered particularly simple 25 and effective, and whereby the efficiency and reliability in operation of a furnace equipped with reversing apparatus of this type is greatly increased. These and other advantageous features of my invention will 30 hereinafter more fully appear in the following description, reference being had to the accompanying drawings, wherein—

Fig. 1 is a diagrammatic view illustrating the application of my improved reversing apparatus to a regenerative furnace of a well known type.

Fig. 2 is a diagrammatic view similar to Fig. 1, showing the parts of my improved reversing apparatus in a different position.

Fig. 3 is a plan view of one of the reversing units to which my improved control is applied.

Fig. 4 is a side view of the apparatus shown in Fig. 1, certain parts being broken away to disclose more clearly the construction thereof.

Fig. 5 is a longitudinal sectional view on the line 5—5 of Fig. 3.

Fig. 6 is a plan view of a control device employed in connection with one of the reversing units.

Fig. 7 is a view in side elevation of the control device shown in Fig. 6.

Fig. 8 is a diagram of a portion of the

wiring for two reversing units and showing 55 in perspective the angular relation between the control wheels of two duplicate reversing units.

Fig. 9 is a diagrammatic view showing the position of the reversing unit with which 60 is associated one of the control wheels shown in Fig. 8.

Fig. 10 is a diagrammatic view of the reversing unit with which is associated the other control wheel shown in Fig. 8. 65

Like reference characters refer to like parts in the different figures.

Referring first to the diagram of Fig. 1, which illustrates the application of my invention to a heating furnace, the furnace 1, 70 of any well known type, is provided at its opposite ends with gas regenerator passages 2, 2' and adjacent air regenerator passages 3, 3', arranged in the manner common to furnaces of this general type. In the use 75 of duplicate reversing instrumentalities for such a furnace, as disclosed in my above mentioned copending patent application, five coterminous flues are arranged at each end of the furnace adjacent the respective 80 regenerators, and hood structures 4 and 4' are disposed in operative relation to the respective sets of flue terminals. In each set of terminals, the gas regenerator passages 2, 2' of the furnace connect with gas 85 regenerator flues 5, 5', and the air regenerator passages 3, 3' connect with air regenerator flues 6, 6'. Separate pairs of stack flues 7, 7' and 7', 7' are arranged between the air 90 and gas regenerator flues 5, 6 and 5', 6', the stack flues being connected to a common stack passage 8. Gas supply flue terminals 9, 9' are also arranged in alinement with the regenerator flue terminals above described. 95

The duplicate reversing instrumentalities are of the construction shown in Figs. 3, 4 and 5, and consists essentially of a pair of hood structures referred to generally as 4 and 4' in Fig. 1, the hoods of each structure being movable in unison and each adapted to bridge over two adjacent flue terminals of its associated set. In either position of the hood structures, as illustrated in Figs. 1 and 2, one air flue 6 or 6' and one gas flue 9 or 9' is always left unbridged, as the case may be. It will be well understood that under these conditions with the hood struc-

tures 4 and 4' in the positions shown in Fig. 1, the passage of air and gas through the furnace 1 is from right to left, whereas when the hood structures 4 and 4' are moved 5 to their other positions, as shown in Fig. 2, the direction of the products of combustion through the furnace is reversed, as indicated by the arrow.

Referring now to Fig. 5, a water seal casting 10 is so formed as to provide the several alined flue terminals 6, 7, 7, 5 and 9 which register with the corresponding passages provided in the brick work 11, the two terminals 7, 7 opening from a single passage 8 15 which leads to the stack. The casting 10 also provides a surrounding rim or flange 12, which is adapted to maintain a sufficient depth of water for sealing purposes around and between all of the flue terminals, as will 20 be readily understood. On opposite sides and near each end of the casting 10 are provided bearing lugs 13, 13, upon which are pivotally mounted alined pairs of bell cranks 14, one crank being provided near 25 each end of the four corners of the casting 10. As best shown in Fig. 4, the cranks at one end of the casting 10 are oppositely disposed from those at the other end of the casting, so that in the position shown, the 30 cranks 14 at the left hand end have their shorter arms directed downwardly, while the cranks 14 at the right hand end have their shorter arms directed upwardly. The long arms of the bell cranks 14 are utilized 35 for the movement of a hood supporting frame 15, which is substantially rectangular in shape, and to which is secured a pair of hoods 16 and 17. The hoods 16 and 17 meet at substantially the center of the frame 15 40 and are provided with downwardly extending flanges 18 that are adapted to dip beneath the water in the casting 10, for the purpose of providing a seal, as hereinafter described.

45 The frame 15 provides at each corner a lug 19, by means of which the long arms of the bell cranks 14 may be connected thereto through shafts 20 extending across the frame 15 through the lugs 19 and connected at their 50 ends to the cranks 14. The long arms of the cranks 14 are parallel and thus provision is made for imparting to the frame 15 and hoods 16 and 17 a parallel motion with respect to the axes of rotation of the cranks 55 14. Links 21 are connected to the short arms of the cranks 14 on each side of the frame 15, each pair of links 21 extending toward each other and being inclosed in a tubular casing 22. Each link 21 is surrounded by a 60 spring 23, which is confined at its ends between a head 24 closing one end of the casing 22 and a collar 25 carried by the link 21, the collar 25 being adapted to slide within the casing 22.

65 In the position of the parts shown in Fig.

4, with the frame 15 and the two hoods 16 and 17 in their extreme right hand positions, the springs 23, two on each side of the apparatus, are under extreme compression and are therefore tending to rock the bell cranks 70 14 in a counterclockwise direction through the collars 25 and links 21. Owing to the forces thus exerted by the springs 23, the act of moving the frame 15 and the hoods 16 and 17 to the left about the centers of the 75 cranks 14 requires only a relatively small force in comparison to that which would otherwise be required to effect the combined translatory and lifting movements of the parts. As this particular arrangement of 80 parts, whereby the above described result is obtained, forms no part of the present invention, and is fully disclosed in my above mentioned copending patent application, no further discussion thereof is deemed necessary herein.

The power required for rocking the cranks 14 in the manner above described is obtained from an electric motor 26 on a pedestal 27 provided at one end of the casting 10. The shaft of the motor 26 is provided with a pinion 28, which is in mesh with a gear 29 mounted at one end of a countershaft 30, the gears being inclosed within a casing 31. The shaft 30 is journalled in a housing 32 extending upwardly from the pedestal 27, and is provided with a worm 33 in mesh with a worm wheel 34. The worm wheel 34 is carried on a transverse shaft 35 which projects at its ends beyond the housing 32, and upon 100 which is mounted a pair of cranks 36. The cranks 36 are connected by rods 37 to the right hand cross shaft 20, to which the long arms of the adjacent cranks 14 are also attached. It is obvious that rotation of the 105 motor shaft will be transmitted to the shaft 35 through the gearing above described, and that a half revolution of the shaft 35 is adapted to effect one complete operation of the hood structure. That is to say, as the 110 cranks 36 move through the lower half of their travel, the hood structure is carried over to the left, from the position shown in Fig. 5, while when the cranks 36 move through the upper half of their travel, the 115 hood structure will be moved from its extreme left hand position back to the position illustrated in Fig. 5. The position which the hood structure occupies when in its extreme left hand position is illustrated 120 diagrammatically in Fig. 2.

Each gas flue terminal 9, 9 is equipped with a swinging cover 38, which is adapted to move on a trunnion shaft 39 supported on the bottom of the casting 10. The cover 38 125 is formed with a projecting lug 40 which is adapted to be engaged by the flange portion 18 running along the bottom of the outside hood 17 of each pair. In the position of the parts illustrated in Fig. 5, that portion 130

of the flange 18 bearing on the lug 40 holds the cover 38 in raised position and thus permits the flow of gas from the flue terminal 9 to the flue terminal 5, which latter is connected to the gas regenerator passage 2 of the furnace, as indicated in Fig. 1. The movement of the hood structure to its left hand position as described above, for the purpose of reversing the furnace, disengages the flange 18 from the lug 40 and allows the cover 38 to descend by gravity so as to cover and effectually seal the gas terminal 9. The arrangement of the parts is such that the cover 38 moves its full distance downwardly and seals the terminal 9 before the flange 18 is entirely lifted out of the water in the casting 10. In this way the escape of any gas past the flue terminal 9 during the operation of reversing is effectually prevented, since the cover 38 descends fully and makes a water seal around the flue terminal before the water seal made by the flange 18 is broken.

With the hood mechanism in the position shown in Fig. 5, the frame 15 is so disposed as to maintain a damper or cover 41 in operative relation to the air regenerator flue terminal 6. This cover 41 is pivotally mounted on the left hand end of the hood 16, as indicated at 42, and the position of the damper 41 may be controlled manually or otherwise by a chain or other suitable connection 43, so as to regulate the amount of air which enters the furnace through the flue 6. When the hood structure moves to the left, as described above, in the act of reversing the furnace and thereby connecting the flue terminal 6 with the adjacent flue terminal 7, the cover 41 will be raised about its pivot 42 and simultaneously carried to an inoperative position beyond the terminals of all the flues, as illustrated diagrammatically in Fig. 10.

It will be understood that the reversing instrumentalities above described are identical in all respects, and that by their arrangement as described in my above mentioned copending application, such instrumentalities are sufficient to take care of the complete reversal of a regenerative furnace. Each hood structure functions with respect to both gas and air, so that any necessity for separate and independent air and gas valves is eliminated. One of the great advantages to be gained by the use of the reversing instrumentalities above described, lies in the fact that such instrumentalities may be placed in close proximity to the air and gas regenerator passages of the furnace, which results in greatly reducing the lengths of the underground flue passages, with a consequent reduction in the wastage of gas when the furnace is reversed. Obviously, the operation of the reversing instrumentalities can be controlled in any desired way, but

in order to permit the convenient control of the operation at a point removed from the furnace, I propose to provide improved electrical control apparatus, whereby the movements of both hood structures will at all times be under the control of the operator, and whereby the most desirable relation between the movements of the separate hood structures may be automatically obtained to reduce the wastage of gas to a minimum. 75

Referring now to Figs. 6 and 7, a control device is mounted within each gear housing 32 adjacent to one of the cranks 36. Each control device comprises a wheel 44 mounted on the shaft 35 and carrying peripherally a generally cylindrical contact drum 45. The drum 45 is adapted to be engaged at times by a pair of contact fingers 46 and 47 that are carried on an arm 48, which is pivotally mounted on the shaft 35, for a purpose to be hereinafter described. Additional contact fingers 49, 50 and 51 are also stationarily disposed in position to engage other portions of the drum 45. 80

As best shown in Fig. 8, the contact drum 45 is irregular in form and is so constructed that only the contact finger 49 remains in engagement therewith during a complete revolution of the wheel 44. The contact finger 46 is adapted to engage only the projection 52 of the drum 45, while the contact finger 51 is adapted to only engage the projection 53. The contact finger 47 is in engagement with the drum 45 except when it registers with the notches 54 and 55 thereof, while the contact finger 50 is in engagement with the drum except when it registers with the notches 56 and 57. The short notches 54 and 56 are diametrically opposed with respect to the axis of rotation of the shaft 35, and the same holds true of the long notches 55 and 57. 90

There is also illustrated in Fig. 8 the wiring of the panel for controlling the operation of the motor 26, together with an arrangement of push buttons whereby the panel may be operated at a point removed therefrom. It is obvious that the panel together with the apparatus for controlling the field strength of the motor 26 may be conveniently placed at some point near the motor 26, whereas the several push buttons may be placed at any desired location on the operating floor where they may be conveniently reached by the operator. The electrical connections between the control panel, the push buttons and the control drum, previously referred to, will now be described. 105

The electric motor 26 comprises an armature 58, a series field winding 59, a shunt field winding 60 and a commutating field winding 61. The control panel comprises a line switch 62, the stationary terminals 63 and 64 of which are connected to a suitable source of electrical energy, the polarity of 110

the terminals being indicated. One of the movable poles 65 is connected to one terminal of the series field winding 59, the other terminal of which is connected to one stationary contact member 66 of a contactor 67. The corresponding movable contact member 68 of the contactor 67 is connected in series circuit relation with the armature 58 and the commutating field winding 61 of the motor 26. The winding 61 is also connected to the other movable contact member 69 of the contactor 67, the corresponding stationary contact member 70 being connected to the other movable pole 71 of the switch 62. One terminal of the closing coil 72 of the contactor 67 is connected to the pole 65, and the other terminal thereof is connected to one stationary contact 73 of a push button having a bridging member 74. The other contact 75 of the push button is connected to the line switch terminal 71 through the contacts 76 and 77 of a push button, in which the bridging member 78 is normally in contact with the members 76 and 77. The contact fingers 47 and 50 of the control device are also connected to the line switch terminal 71 through the normally closed contacts 76 and 77 of this push button. When it is desired to start the motor 26, it is only necessary to depress the bridging member 74 of the upper push button, which completes the circuit of the closing coil 72 and causes the contactor 67 to close. This connects the armature 58 of the motor 26, across the terminals of the line switch 62 in series with the field windings 59 and 61. A lamp 79, located above the push buttons and connected across the terminals of the armature 58, is then lighted and indicates to the operator that the motor 26 has started.

As soon as the motor starts, the shaft 35 also starts to turn, whereupon the contact fingers 46 and 47 will immediately engage the contact drum 45. When this occurs, the circuit of the closing coil 72 is completed through the contact finger 47 and the contact finger 49, which is always in engagement with the drum 45 and is connected to one of two contacts 80 which are automatically bridged by a member 81 upon the closing of the contactor 67. The motor will then continue to operate, even though the bridging member 74 of the upper push button be released by the operator, due to the fact that the circuit of the closing coil 72 is maintained by the engagement of the contact 50 with the drum 45 before the contact 47 reaches the notch 55. The continued operation of the motor will then cause the frame 15 and hoods 16 and 17 to be lifted from the position shown in Fig. 4, whereupon the cover 38 will close the gas flue 9 before the raising of the flange portions 18 breaks the water seal. The motor 26 will

continue to operate until the shaft 35 has completed one half of a revolution, whereupon the contact finger 50 will register with the notch 56 and break the holding circuit of the closing coil 72 of the contactor 67. At this point in the revolution of the shaft 35, the hoods 16 and 17 will have reached their extreme left hand position, so that the air and gas regenerator flues 5 and 6 will be connected to the stack flues 7, 7, as indicated diagrammatically in Fig. 2. The motor 26 will then remain stationary until it is again started by depressing the bridging member 74 of the upper push button, whereupon first the contact 50 and then the contact 47 will again engage the drum 45 and complete the holding circuit of the closing coil 72. The motor will thus continue to operate to move the hood structure to the right until the shaft 35 has nearly completed another half revolution; at this moment the contact 47 will reach the notch 54 and the motor will be stopped with the hood structure again in the position of Fig. 5 with the cover 38 open. The operation of the motor 26 can be interrupted at any time, while the shaft 35 is turning through one half of a revolution, by depressing the bridging member 78 of the lower push button, which interrupts the circuit between the closing coil 72 and the line switch terminal 71. Means are also provided for reversing the direction of rotation of the motor 26 during the first part of a half revolution of the shaft 35. The reversing means consists of a reversing switch 82, the contacts of which are so arranged as to reverse the direction of current flow through the armature 58 when the contacts of this switch are closed. One terminal of the closing coil 83 of the reversing switch 82 is connected to the line switch terminal 65, and the other terminal of this coil is connected to one stationary contact 84 of a push button, the bridging member 85 of which is normally out of engagement with the contact 84. The other contact member 86 of this push button is connected to the contact finger 46 of the control device. The contact finger 46 is adapted to be engaged by the drum 45 only when its projection 52 is in engagement with the finger 46, so that the circuit of the closing coil 83 can only be completed during the first part of the upward movement of the hoods 16 and 17 to the left which results in lowering the cover 38. In other words, it is only possible to reverse the direction of rotation of the shaft 35 while the flange portions 18 are still in the water and the flues are sealed. The object of this is to provide means whereby the amount of gas passing through the flue 9 can be varied by raising or lowering the hoods slightly and thereby effecting the elevation of the cover 38 through its engagement by the

flange 18. It is only possible for the operator to reverse the motor when the contact finger 46 is in engagement with the projection 52 of the drum 45.

As also shown in Fig. 8, the contact finger 51 of the right hand control device is connected to the circuit of the control panel of the left hand hood structure at a point between one terminal of the closing coil 72' and the stationary contact 73' of the top push button. The contact finger 51 is adapted to be engaged by the projection 53 of the drum 45 just before the contact finger 50 registers with the notch 56 of the drum 45 and thereby interrupts the energizing circuit of the coil 72', as previously described. In other words, just before the shaft 35 completes one half of a revolution and then stops, the circuit of the closing coil 72' of the other control panel is completed by the engagement of the contact finger 51 with the projection 53, whereupon the motor of the other hood mechanism starts to operate. The contact finger 51 is in engagement with the projection 53 only long enough to allow the drum 45' to start to turn, whereupon the circuit of the closing coil 72' is completed, by the bridging of contact fingers 49' and 50' by the drum 45'. The motor of the left hand hood mechanism will be automatically stopped as soon as the shaft 35' has completed one half of a revolution, as will be readily understood. Disconnecting switches 87 and 87' are provided between the fingers 51 and 51' and the coils 72 and 72', respectively, so that the motors may be operated independently of each other.

From the foregoing it is apparent that I have provided means for controlling the operation of the duplicate hood structures of a furnace, whereby the position occupied by the hoods is at all times under the control of an operator who may be conveniently stationed at some desired point on the operating floor remote from the hood actuating mechanism. Assuming that the hood structures occupy the positions diagrammatically illustrated in Figs. 9 and 10, it is apparent that the flow of gas and air through the furnace will then be from right to left, as also shown in Fig. 1. During the operation of the furnace with the hood structures in this position, it is possible for the operator to closely control the amount of gas admitted to the furnace by operating the forward and reverse push buttons as described above, until the required degree of heat is obtained.

When it is desired to reverse the direction of gas and air through the furnace, it is only necessary for the operator to depress the top bridging member 74 and hold it down until the lamp 79 lights, whereupon it may be released. The motor 26 will then turn the shaft 35 until it has completed one

half a revolution, whereupon it will be automatically stopped. Just before the shaft 35 has completed one half a revolution, or in other words, just after the flange portions 18 have completed the water seals for the new positions of the hoods 15 and 16, the motor of the left hand hood structure will be automatically started by the engagement of the contact 51 with the projection 53. The left hand hood structure is then moved from the position shown in Fig. 10 to a position corresponding to that occupied by the structure in Fig. 9, whereupon the flow of gas and air from the furnace will be from left to right, the right hand hood structure then occupying a position corresponding to that occupied by the structure in Fig. 10. In this way the entire movement of the hood structures necessary for completely reversing the flow of air and gas through the furnace is automatically carried out following the single act on the part of the operator in depressing the top push button.

Obviously, the above described automatic operation of the two hood structures is most efficient from the standpoint of fuel consumption, owing to the fact that no fresh gas is admitted to the furnace following the shutting off of gas in the right hand flue 9 until the right hand hood structure has almost completed its movement and is adapted to direct the discharge of the products of combustion into the stack flue 8. In other words, during this movement there is time for the gas remaining in the furnace to be consumed and fresh gas is not admitted to the furnace and gas regenerator by the opening of left hand flue 9' until the combustion of the old gas is complete. Obviously this result could not be obtained if the operation of the left hand hood structure were entirely dependent upon the judgment of the operator, as he would be likely to start the movement of the left hand hood structure to admit fresh gas before the gas remaining in the furnace was completely consumed. It is also obvious that the operation of both hood structures is at all times under the control of the operator, so that the movement thereof can be interrupted whenever desired by merely depressing either one of the lower push buttons which are adapted to interrupt the circuit of the closing coils of the starting switches.

In addition to the above described means for automatically controlling the operation of the hood structures, I have provided additional means whereby either hood structure may be caused to come to rest at some intermediate point in its travel from one extreme position to the other, so that the cover 38 will be swung only part way open instead of all the way open. Under certain conditions, this position of the hood struc-

ture may be desirable, so as to obtain a partial throttling of the gas supply to the furnace. As previously described with reference to Figs. 6 and 7, the contact fingers 46 and 47 are mounted on the movable arm 48, and it is obvious from an inspection of Fig. 8, that the fingers 46 and 47 can be caused to register with the notch 54 in the drum 45 before the motor shaft has completed one half of a revolution by merely advancing the arm 48. This has the effect of checking the right hand movement of the hood structure before the cover 38 is raised to the position of Fig. 5. An operating rod 88 is connected to the arm 48, so that the position of the arm 48 can be controlled from the operating floor along with the push buttons, if desired. In this way a very close adjustment of the gas supply can be obtained.

While I have shown my invention as applied to a particular arrangement of reversing apparatus as disclosed in my above mentioned copending application, it is not so limited, but may as well be applied to other reversing apparatus operating on the same general principles. I desire therefore that only such limitations be imposed thereon as come within the scope of the appended claims.

I claim,

1. The combination with cooperating duplicate reversing devices for a regenerative furnace, of electrical controlling mechanism therefor, operable selectively to procure the reversing movements of said devices in timed relation or to procure the independent movement of either of them.

2. The combination with cooperating duplicate reversing devices for a regenerative furnace, of electrical controlling mechanism therefor operable when desired to vary the flow of gaseous fuel through either of said devices.

3. The combination with cooperating duplicate reversing devices for a regenerative furnace, of electrical controlling mechanism therefor operable selectively to procure the reversing movements of said devices in timed relation or to vary the flow of gaseous fuel through either of them.

4. The combination with cooperating duplicate reversing devices for a regenerative furnace, of electrical controlling mechanism therefor operable when desired to vary the flow of gaseous fuel through either of said devices by limited movement thereof from the normal full-open gas supply position of such device.

5. The combination with cooperating duplicate reversing devices for a regenerative furnace, of electrical controlling mechanism therefor operable when desired to vary the flow of gaseous fuel through either of said

devices by bringing such device to rest, in the act of reversal, at an intermediate point in its traverse.

6. The combination with cooperating duplicate reversing devices for a regenerative furnace, of electrical controlling mechanism therefor, comprising means for automatically procuring the reversing movements of said devices in timed relation, and means for selectively procuring the stoppage of one of said devices, in the act of reversal, at an intermediate point in its traverse.

7. The combination with cooperating duplicate reversing devices for a regenerative furnace, of electrical controlling mechanism therefor, comprising means for automatically procuring the reversing movements of said devices in timed relation, and means for manually controlling the extent of traverse of one of said devices in its movement toward fuel-supplying position.

8. The combination with cooperating duplicate reversing devices for a regenerative furnace, of electrical controlling mechanism therefor, comprising an actuating motor for each of said devices, means for automatically procuring the operation of said motors in timed relation, and means for independently discontinuing the operation of one of said motors, during the act of reversal.

9. The combination with cooperating duplicate reversing devices for a regenerative furnace, of electrical controlling mechanism therefor, comprising an actuating motor for each of said devices, means for automatically procuring the operation of said motors in timed relation, and means for selectively procuring the operation of one of said motors, for a limited duration, to vary the volume of gaseous fuel flow through its associated device.

10. The combination with cooperating duplicate reversing devices for a regenerative furnace, of an electric motor for moving each of said devices, a control device for each motor, means for coordinating the operations of said control devices, for the actuation of said reversing devices in timed relation, and means for manually procuring the independent operation of said control devices, whenever desired.

11. In apparatus of the class described, the combination with a set of furnace flues, a cover for one of said flues, a movable reversing device operative with respect to said flues and adapted by its movement in one direction to close said cover, an electric motor, for driving said reversing device and a source of electrical energy, of means for connecting said motor to said source for driving said reversing device in one direction of movement, and a control device operable in timed relation with said reversing

device for permitting reversal of the said motor during a limited portion of the movement of said reversing device by said motor to vary the degree of closing of said cover.

12. In apparatus of the class described, the combination with a set of furnace flues, a cover for one of said flues, a movable reversing device operative with respect to 10 said flues and adapted by its movement in one direction to open said cover, an electric motor for driving said reversing device and a source of electrical energy, of means for connecting said motor to said source for 15 driving said reversing device, a control device operable in timed relation with said reversing device for automatically disconnecting said motor from said source after said reversing device has opened said cover a

predetermined amount, and means for adjusting the operation of said control device to vary the degree of opening of said cover.

13. In apparatus of the class described, the combination with a pair of movable hood structures, an electric motor for moving each of said hood structures and a device for controlling the operation of each of said motors so as to cause a motor to move its hood structure a predetermined amount, of means for coordinating the operation of 25 said control devices, whereby the operation of either one of said control devices will cause first one and then the other of said hood structures to be moved through its complete travel, and means for rendering 30 the operation of said control devices independent of each other.

GEORGE H. ISLEY.
